(57) **CLAIM**

The ornamental design for an angle mounted weapon sight, as shown and described.

DESCRIPTION

FIG. 1 is a front, top and right side perspective view of an angle mounted weapon sight, showing my new design. The broken lines showing the outline of a partial weapon receiver are for illustration purposes only and form no part of the design;

FIG. 2 is a front elevational view thereof;

FIG. 3 is a right elevational view thereof;

FIG. 4 is a left elevational view thereof;

FIG. 5 is a top plan view thereof;

FIG. 6 is a bottom plan view thereof; and,

FIG. 7 is a back elevational view thereof.
